Primary Examiner — Mehri F Bajoul(74) *Attorney, Agent, or Firm* — Cramer Patent & Design, PLLC; Aaron R. Cramer(57) **CLAIM**

The ornamental design for a billiard stroke training aid, as shown and described.

DESCRIPTION

FIG. 1 is a top front right perspective view of a billiard stroke training device in an exploded state, showing the stand, first and second holder components;

FIG. 2 is a top rear left perspective view thereof;

FIG. 3 is a front elevation view thereof;

FIG. 4 is a rear elevation view thereof;

FIG. 5 is a right elevation view thereof;

FIG. 6 is a left elevation view thereof; and,

FIG. 7 is a top plan view thereof.

FIG. 8 is a bottom plan view thereof;

FIG. 9 is a top front right perspective view of the billiard stroke training devise with the base and the first holder component, shown separately for ease of illustration; and,

FIG. 10 is a top front right perspective view of the billiard stroke training devise with the base and the second holder component, shown separately for ease of illustration.
